UNITED STATES PATENT OFFICE.

CARL E. BROWN, OF COLUMBUS, OHIO, ASSIGNOR TO PARKER MANUFACTURING COMPANY, OF DAYTON, OHIO.

OIL-BURNER.

1,398,254.

Specification of Letters Patent. Patented Nov. 29, 1921.

Application filed July 9, 1919, Serial No. 309,694. Renewed October 3, 1921. Serial No. 505,113.

To all whom it may concern:

Be it known that I, CARL E. BROWN, a citizen of the United States, residing at Columbus, in the county of Franklin and 5 State of Ohio, have invented a new and useful Oil-Burner, of which the following is a specification.

The device forming the subject matter of this application is an oil burner of that 10 general type in which a U-shaped generator is employed in connection with a box-like casing having flues through which one arm of the generator passes. One object of the invention is so to improve structures of the 15 kind mentioned, that the generator may be shifted transversely to coöperate with the water front or the oven of a cook stove.

Another object of the invention is to provide novel means for limiting the longitudinal sliding movement of the generator.

A mechanic may work changes, within the scope of what is claimed, in the structure shown and described, without departing from the spirit of the invention.

25 In the drawings:—Figure 1 is a side elevation wherein parts are broken away; Fig. 2 is a section on the line 2—2 of Fig. 1; Fig. 3 is an end elevation; Fig. 4 is a cross section on the line 4—4 of Fig. 1.

30 The device includes a box-like casing 1 comprising a body 2 carrying a top 3 having a depending marginal flange 4 coacting with the body 2 to hold the top thereon against lateral movement, the top having an 35 upstanding marginal flange 5 adapted to retain ashes, asbestos or the like, (not shown), for the reception of a priming charge as hereinafter described. The flange 5 carries an upstanding stop 6 located at one end of 40 the casing. The top 3 is provided with conical flues 7 provided with transversely elongated openings 8. The numeral 9 denotes a generator in the form of a U-shaped pipe including a lower arm 10 and an upper 45 arm 11. The lower arm 10 passes through the openings 8 in the flues 7 and is terminally closed by a cap 12. Suitable couplings and connections 14 unite the arm 11 with a valve 15, fuel being supplied to the 50 valve by a flexible tube 16. Flame spreaders 17 are mounted on the arm 11 of the generator 9 and are disposed above the flues 7. The arm 10 of the generator 9 is provided

with combustion orifices 18 located within the flues 7. The numeral 19 denotes a U-shaped support secured at 21 to the top 3 of the casing 1. The lower arm 10 of the generator 9 passes through the support 19, the support having a straight upper edge 20 on which the upper arm 11 of the generator rests. The generator 9 is slid endwise in the openings 8 of the flues 7 until the cap 12 abuts against the stop 6. The combustion orifices 18 then are outside of the flues 7. The valve 15 is opened and a 65 priming charge is permitted to trickle out of the orifices 18 into the ashes on the top 3. The valve 15 then is closed and the generator 9 is moved to the right (Fig. 1) until the orifices 18 are disposed inside of the 70 flues 7. The oil in the ashes is ignited and the generator is heated. The valve 15 then is opened and the gas is ignited at the orifices 18, the gas being generated in the member 9, in a well known way. Air passes 75 upwardly into the body 2 and through the flues 7, a mixture thus being produced as understood by those skilled in the art.

80 A salient and important feature of the device remains to be discussed. The openings 8 are not mere apertures, in which the lower arm 10 of the generator is guided for endwise sliding movement: they are elongated transversely of the structure, to such an extent that the generator 9 can be shifted 85 transversely an appreciable amount, that is, through a distance approximating the width of the casing 1. This operation permits the generator to be shifted forwardly, to assume a position close to the water front of a cook 90 stove, or to be shifted rearwardly, to assume a position close to the oven of the stove. During the transverse shifting movement of the generator 9, the upper arm 11 of the generator slides on the straight edge 95 20 of the support 19.

I claim:—

A burner comprising a casing having a flue provided with openings; a support on the casing; and a U-shaped generator embodying an upper arm slidably mounted on the support, and a lower arm slidably mounted in the openings, the lower arm having a combustion orifice normally located within the flue and adapted to be disposed 105 outside of the flue when the generator is

slid endwise, the openings in the flue being elongated transversely of the casing, whereby the generator may be slid transversely from a point relatively close to one side of the casing, to a point relatively close to the opposite side of the casing.

In testimony that I claim the foregoing

as my own, I have hereto affixed my signature in the presence of two witnesses.

CARL E. BROWN.
